UNITED STATES PATENT OFFICE.

ROBERT WARG, OF MILWAUKEE, WISCONSIN.

CENTRIFUGAL FAN.

1,156,118.

Specification of Letters Patent. Patented Oct. 12, 1915.

Application filed April 13, 1914. Serial No. 831,531.

To all whom it may concern:

Be it known that I, ROBERT WARG, a citizen of the United States, and resident of Milwaukee, in the county of Milwaukee and 5 State of Wisconsin, have invented new and useful Improvements in Centrifugal Fans, of which the following is a description, reference being had to the accompanying drawings, which are a part of this specification.

10 This invention relates to improvements in centrifugal fans and more particularly to fans or pumps in which the fluid to be moved is taken into the fan axially and is discharged circumferentially.

15 It is one of the objects of the present invention to provide a centrifugal fan of great rigidity and efficiency which is of simple construction and is well adapted for the purpose described.

20 A further object of the invention is to provide a centrifugal fan having a rotary member constructed of thin elongated blades arranged in substantially drum-like form to provide a comparatively large intake opening and chamber to permit the free unobstructed ingress of air to the blades.

25 A further object of the invention is to provide a centrifugal fan in which the drum is formed of two circumferential lines of 30 blades of which the blades of the inner line are arranged to draw and deflect the fluid inwardly toward the inner end of the blades in order to equalize the work on all portions of the blades and form an efficient construction.

35 A further object of the invention is to provide a centrifugal fan in which the fluid to be moved is carried by the fan blades a short distance and is then discharged centrifugally from the periphery of the drum 40 of which the blades form a part.

45 A further object of the invention is to provide a centrifugal fan in which the drum is formed of two circumferential lines of 50 blades extending at an oblique angle with relation to the axis of rotation of the drum and also in which the blades of the inner circumferential line extend obliquely at angles crossing the angles of the outer circumferential line.

55 With the above and other objects in view, the invention consists of the improved centrifugal fan and its parts and combinations as set forth in the claims, and all equivalents thereof.

In the accompanying drawing in which

the same reference characters indicate the same parts in all of the views: Figure 1 is a side view of the improved fan, portions being broken away to show interior construction; Fig. 2 is a vertical central section view on a larger scale, of the rotary member of the fan and a portion of the casing; Fig. 3 is a peripheral detail view of the rotary member; Fig. 4 is a sectional detail view taken on line 4-4 of Fig. 3; Fig. 5 is a similar view of a modified form of rotary member; and Fig. 6 is a transverse sectional detail view of a slightly modified form of a rotary member blade.

Referring to the drawing the numeral 8 indicates a casing of spiral contour which is provided with a comparatively large intake opening 9 on one side and a peripheral discharge opening 10 formed in a trunk extension 11 projecting from the periphery thereof. This casing is of ordinary construction and is provided with a journal bearing 12 on its side portion opposite to the inlet opening. The bearing is pivoted to the casing to provide for alining the bearing with a shaft 13 which is journaled in the bearing and extends therethrough and into the casing. The rotary fan member 14 mounted on the shaft within the casing is of drum-like formation 15 to provide a comparatively large inlet chamber 15 which is of a diameter approximately coinciding with the diameter of the intake opening 9 of the casing and is in alinement therewith.

The rotary drum-like member comprises a pair of annular head plates 16 and 16' which are spaced apart by the inner and outer circumferential lines of elongated closely positioned radial blades 17 and 17'. The inner line of blades extend obliquely from the annular rear plate 17 to the front plate 17' and in a direction toward the direction of rotation of the rotary member, so that, in drawing in the fluid, the fluid will be engaged and deflected toward the rear annular plate 17 of the said member in its passage between the blades. The outer circumferential line of blades is similar to the inner line except that they extend obliquely in the opposite direction or in a direction receding from the direction of rotation of the drum. This oblique arrangement of the outer blades serves to deflect the engaged fluid toward the front plate of the drum thus providing a construction in which all portions of the blades do their proportionate share of the

work with the result that a large volume of fluid may be moved in an efficient manner. The opposite ends of the blades are bent at angles to bear against the opposite annular plates as indicated by the numeral 18 and rivets 19 passing through these bent ends and the plates securely fasten the parts together.

The rotary drum is connected to the shaft 10 18 by a hub 20 provided with a conical flange 21 upon which radial spokes 22 are mounted. The outer ends of these spokes are secured to the inner annular flange 16. It will be noted that the conical hub flange 15 and the spokes extend at an angle toward the rear annular plate 17 in order to guide the incoming fluid toward the rear portions of the blades.

In the modified form shown in Fig. 5 the 20 inner and outer blades 23 are combined to form one circumferential line in which one-half of the blades extend in a direction opposite to the other half. Each inner blade is provided with outer transverse recesses 25 or cuts 24 extending for a distance approximately one-half its width at a plurality of points, to receive the corresponding inner cut portions of the outer blades which extend in the opposite direction. This construction provides a plurality of diamond-shaped spaces 25 which serve to draw in the fluid and discharge it tangentially therefrom in substantially the same manner as in the first form mentioned.

35 In order to increase the strength of the blades without increasing the thickness of the material, it is desirable, in some cases, to bend a portion 26 of the blade in the manner shown in Fig. 6, the bent portion being formed on the outer edge of the blade.

40 From the foregoing description it will be seen that the centrifugal fan is so constructed that all parts of the blades share their proportionate load with the result that an efficient fan is provided.

45 What I claim as my invention is:

1. A centrifugal fan, comprising a rotary drum-like member having numerous elongated blades arranged lengthwise obliquely with relation to the axis of rotation of the member to form comparatively a large intake chamber, approximately one half of the number of blades extending obliquely in the opposite direction from the remaining 55 blades, one end of the said member being open to permit unobstructed ingress of the fluid to be moved, and supporting means for said member which will freely permit the tangential escape of the fluid from the 60 blades of said member.

65 2. A centrifugal fan, comprising a rotary drum-like member having a plurality of circumferential lines of numerous elongated blades arranged lengthwise obliquely with relation to the axis of rotation of the mem-

ber to form comparatively a large intake chamber, the blades of one circumferential line extending at an angle with relation to the blades of the adjacent circumferential line, one end of said member being open to 70 permit unobstructed ingress of the fluid to be moved, and supporting means for said member which will permit the free tangential escape of the fluid from the blades of said member.

75 3. A centrifugal fan, comprising a rotary drum-like member having a plurality of circumferential lines of numerous elongated blades arranged lengthwise obliquely with relation to the axis of rotation of the member to form comparatively a large intake chamber, the blades of one circumferential line extending at an angle with relation to the blades of the adjacent circumferential line and crossing the radial plane of said 80 blades, and supporting means for said member which will permit the free tangential escape of the fluid from the blades of said member.

85 4. A centrifugal fan, comprising a rotary drum-like member having an inner and an outer circumferential line of numerous elongated blades arranged lengthwise obliquely with relation to the axis of rotation of the said member to form comparatively a large 90 intake chamber, one end of said member being open to permit the ingress of the fluid to be moved, the blades of the inner circumferential line being arranged to direct the fluid passing between the said blades toward 100 the rear portion of the said member and the blades of the outer circumferential line being arranged to direct the fluid passing between said blades toward the front portion of said member, and supporting means 105 for said member which will permit the free tangential escape of the fluid from the blades of said member.

5. A centrifugal fan, comprising a pair 110 of spaced annular plates, inner and outer circumferential lines of numerous elongated blades extending obliquely from plate to plate and connected thereto, the blades of one circumferential line extending obliquely in the opposite direction to the blades of the 115 other line, one of said plates having a central opening, a hub portion connected to one of the plates, and supporting means for said hub portion which will permit the free tangential escape of the fluid from the blades.

120 6. A centrifugal fan, comprising a pair of spaced annular plates, an inner and an outer circumferential line of numerous elongated blades extending obliquely from plate to plate and connected thereto the blades 125 of one circumferential line extending obliquely in the opposite direction to the blades of the other line, one of said plates having an inlet opening of a diameter approximately coincident with the diameter 130

formed by the inner edges of the inner circumferential line of blades, a hub portion connected to one of the plates, and a supporting means for said hub portion which 5 will permit the free tangential escape of the fluid from the blades.

7. A centrifugal fan, comprising a pair of spaced annular plates, an inner and an outer circumferential line of numerous elongated blades extending obliquely from plate 10 to plate and connected thereto, one of said plates having an inlet opening of a diameter approximately coincident with the diameter formed by the inner edges of the inner cir-

cumferential line of blades, the blades of 15 one circumferential line extending at an angle with relation to the blades of the other circumferential line, a hub portion connected to one of the plates, and a supporting means for said hub portion which will 20 permit the free tangential escape of the fluid from the blades.

In testimony whereof, I affix my signature, in presence of two witnesses.

ROBERT WARG.
